UNITED STATES PATENT OFFICE.

ELISHA E. MAGGARD, OF MOREHEAD, KENTUCKY.

LAMP-HOUSE FOR PROJECTING APPARATUS.

1,192,658.

Specification of Letters Patent. Patented July 25, 1916.

Application filed December 19, 1913. Serial No. 807,754.

To all whom it may concern:

Be it known that I, ELISHA E. MAGGARD, a citizen of the United States, residing at Morehead, in the county of Rowan and State of Kentucky, have invented new and useful Improvements in Lamp-Houses for Projecting Apparatus, of which the following is a specification.

The invention relates to lamp houses for projecting apparatus, and more particularly to lamp houses for use in connection with motion picture machines, and has for an object to provide a lamp house of a simple construction which will permit of readily 10 adjusting the usual carbons or electrodes, and which, furthermore, is so arranged and constructed that it can be readily cleaned.

The invention contemplates, among other features, the provision of a lamp house 20 adapted to contain the usual carbons and which, by means of suitable mechanism, can be conveniently adjusted, so that a uniform light can be produced when the lamp house is used in connection with projecting apparatus such as motion picture machines and the like.

A still further embodiment of the invention resides in a structure so arranged and constructed that it can be readily opened 30 for the purpose of cleaning the interior thereof and also for the purpose of removing broken or used pieces of carbons.

In the further disclosure of the invention reference is to be had to the accompanying 35 drawings, constituting a part of this specification, in which similar characters of reference denote corresponding parts in all the views, and in which:

Figure 1 is a fragmentary perspective 40 view looking at the rear of the lamp house; Fig. 2 is a vertical longitudinal sectional view taken through the lamp house; and Fig. 3 is a vertical transverse sectional view showing the mechanism for operating the 45 carbons.

Referring more particularly to the views, I disclose a base 10 supporting a casing 11 constituting the body of the lamp house and which is provided with the usual condenser lenses 12. Mounted to swing on the rear 50 end of the casing is a substantially semi-spherical closure 13 adapted to normally close the casing and secured by a suitable catch (not shown). A block 14 preferably

made of porcelain is secured to the outer 55 curved face of the closure 13 by means of suitable screws 15 and journaled in the block is a shaft 16, on which is keyed a toothed wheel 17, the said shaft having one end projecting exteriorly of the box and having 60 a knurled operating wheel 18 whereby rotation can be imparted to the toothed wheel 17. A second shaft 19 is journaled in the block 14 and keyed thereon is a toothed wheel 20 preferably having a hub portion 65 21 thereof formed of some insulating material, with the toothed wheel 20 in mesh with the toothed wheel 17.

Mounted to slide in the block and extending 70 through suitable apertures in the closure 13 are carbons 22, 23, which converge toward their inner ends and at which point the light is adapted to be produced. Keyed 75 on the shaft 16 is a serrated wheel 24 engaging the carbon 22 and keyed upon the shaft 19 is a serrated wheel 25 engaging the carbon 23. Now it will be apparent that by turning the member 18, rotation will be imparted to the toothed wheel 17, thus also rotating the toothed wheel 20 and thus through 80 the medium of the shafts 16 and 19 imparting a rotation to the wheels 24, 25, whereby the carbons 23, 22 can be relatively advanced or retreated within the casing 11 and simultaneously operated. 85

Spring-like contact members 26, 27 are secured within the block 14 and bear against the carbons 22 and 23 respectively, thus not only holding the carbons in frictional engagement with the serrated wheels 24, 25, 90 but also constituting the means for conveying the electric current for illuminating purposes, to the carbons by means of suitable wires 28, 29 respectively, connecting with the respective contact members 26 and 27 95 and leading to the source of electric energy.

Now from the foregoing description it will be seen that the carbons are relatively insulated by being arranged in the porcelain block 14 as mentioned, and can be readily 100 adjusted from the exterior of the casing. Should the carbons become worn out or broken, the closure 13 can be readily swung into open position so that the operator can easily have access to those portions of the 105 carbons which normally lie in the casing for the purpose of removing the broken or worn out carbons, and with this construction the

carbons can also be readily cleaned while the interior of the casing is also accessible for cleaning purposes.

Having thus described my invention, I
5 claim:

The combination with a lamp house, of a substantially semi-spherical shaped closure 15
swingingly mounted on the rear of the lamp house, an arcuate shaped block fixed to the
10 said closure, spaced axles journaled transversely in said block, gears fixed to the said
axles and meshing with each other, carbons
slidably fitted in the blocks in forwardly con-

vergent relation to each other for projection through the closure into the lamp house, 15
feed wheels mounted on the axles and en-
gaging the carbons to move the same, and a
hand knob mounted on the end of one of
the axles exteriorly of the block.

In testimony whereof I affix my signature 20
in presence of two witnesses

ELISHA E. MAGGARD.
